BANK PROTECTING MEANS

Clyde R. Tigert, Upland, Calif.

Application April 7, 1933, Serial No. 664,967

1 Claim. (Cl. 20—1.01)

This invention relates to bank protecting devices and has for its object the production of a simple and efficient means for protecting a bank teller and others against hold-ups by bank bandits and similar criminals.

One of the principal objects of this invention is the production of a simple and efficient means releasable by a teller or other operator, for automatically projecting a shield in front of the teller, 10 and at the same time discharging a charge of tear gas in the face of the would-be hold-up bandit.

Another object of this invention is the provision of a simple and efficient means for automatically moving the protector shield to an extended position behind which the teller may take 15 refuge to prevent personal injury to himself.

A further object of this invention is the provision of a simply designed shield which will prevent bullets impacting against the shield from rocketing off with the danger of injury to other persons.

A still further object of this invention is the production of a simple and efficient mechanism for controlling the automatic discharge of tear 20 gas and the automatic extension of the protector shield to an operative position simultaneously upon the release of a trigger mechanism to be operated by the foot of the teller or other operator.

With these and other objects in view, this invention consists in certain novel constructions, combinations and arrangements of parts as will be hereinafter fully described and claimed.

In the drawings:—

Figure 1 is a rear elevation of a bank teller's cage, certain portions of the apparatus being shown in section, the shield and cartridge discharge mechanism being shown in a set or cocked position;

Figure 2 is a section taken on line 2—2 of Figure 1;

Figure 3 is a section taken on line 3—3 of Figure 1;

Figure 4 is an enlarged side elevation of the trigger mechanism for releasing the cartridge discharge plunger;

Figure 5 is a section taken on line 5—5 of Figure 1;

Figure 6 is an enlarged vertical section taken on line 6—6 of Figure 1;

Figure 7 is a fragmentary inside view of the lower portion of the shield showing the lifting spring attached thereto; and

Figure 8 is an enlarged side elevation partly in section of the cartridge discharge plunger supporting bracket and releasing trigger.

By referring to the drawings, it will be seen that 1 designates the conventional counter as employed in banks and other institutions of similar character, which supports a cage 2 having suitable bars 3. At the lower end of the bars 3 is mounted a shield rail 4 having a plurality of perforations 5 arranged in spaced relations for the purpose of discharging tear gas or other medium at a selected time in the face of a would-be criminal, or hold-up bandit. The shield rail 4 preferably extends around the service opening 6 and the discharge openings or perforations 5 in the rail 4 communicate with a feed passage 7, the feed passage 7 communicating with a cartridge containing cylinder 8 preferably hung below the counter 1, as shown in Figures 1 and 3, in which a suitable tear gas cartridge or other medium 9 is mounted, this cartridge 9 being adapted to be fired by a spring pressed plunger 10 carried by the hanger bracket 11 and working therethrough, as shown in Figures 1, 3 and 8. The plunger 10 carries a coil spring 12 which is interposed between the bottom of the hanger bracket 11 and the trigger engaging disc 13, normally exerting an expansive upward movement upon the plunger 10 for directing the plunger 10 upwardly to discharge the tear gas cartridge 9 as soon as released. The hanger bracket 11 is provided with a depending lip 14 upon which is pivotally mounted the plunger engaging trigger 15 by means of a pivot pin 16, as shown in Figure 8. This trigger 15 is provided with an overhanging tongue 17 which engages the disc 13 of the plunger 10 and normally holds the plunger 10 in a cocked or retracted position. The trigger 15 is provided with a projecting arm 18, which arm 18 normally rests in engagement with a laterally extending lug or pin 19 carried by one side near the bottom of the vertically moving shield 20.

Extending through the counter and normally hanging below the counter, is the shield 20 previously mentioned, which shield is preferably provided with a rail 21 along its upper edge adapted to normally rest in a countersunk groove 22 formed in the top of the counter. This shield 20 is preferably substantially V-shaped in cross-section having its apex 23 facing toward the front of the cage, the side edges of the shield 20 being curved in a forward direction to produce substantially vertically extending semi-circular concavo-convex side walls 24, the shield being so constructed as to prevent the rocketing of bullets discharged to impact against the shield and prevent the flying of the bullets off at a tangent with 45 50 55

the danger of injuring innocent bystanders. As shown in Figure 2, the marginal edges of the shield are curbed backwardly to extend substantially parallel with the respective front inclined faces of the V-shaped shield 20. The body of the shield 20 is also provided with a rail or stop flange 25. The flanges at the top and bottom will also constitute an efficient means for stiffening and bracing the shield and this shield is adapted to pass through a suitable channel or slot 26 formed in the counter, which will also assist in maintaining the shield in its proper shape and guide the shield in its upward movement. The lower end of the shield 20 is preferably braced by means of the bracing straps 27 which are secured to the rear face of the shield near the lower end thereof, and these straps pass around the hanger track 28, which track is substantially U-shaped in structure having laterally extending feet 29 secured to the under face of the counter 1. These bracing straps will constitute runners for traveling on the track 28 and assist in keeping the shield 20 in proper alignment in its travel.

Secured to the rear face of the shield 20 near the lower end thereof, is a trigger engaging bracket 30 which projects rearwardly and is adapted to be engaged by the hooked shaped end 31 of the foot releasing trigger 32, which trigger 32 is pivotally secured, as at 33, to a supporting bracket 34 which is anchored upon the transversely extending bar 35 of the hanger track 28. The trigger 32 is provided with a rearwardly extending foot engaging or treadle tongue 36 which is adapted to be engaged by the foot of the operator, and as this treadle tongue is depressed, the hooked shaped end 31 will be drawn out of engagement with the bracket 30. The hooked shaped end 31 is normally held in engagement with the bracket 30 by means of the coil spring 37 which is anchored at one end to the bracket 34, as shown in Figure 6, and at the other end, as at 38, as is also shown in Figure 6. The end of the hook 31 and the edge of the bracket 30 are properly beveled to facilitate engagement.

Secured to the front face of the shield 20 near the lower end thereof, is a spring engaging shoe 39 which is provided with a laterally extending flange 40 preferably turned up slightly near its side edge and under which extends a contractile coil spring 41, the ends of the spring 41 being connected to the underface of the counter 1 by means of suitable eyelets 42. The spring 41 passes across the ends of the flange 40 and lies close to the shield 20, as shown in Figure 2. This

structure will tend to prevent the spring 41 from accidentally jumping out of position.

The operation of the device is as follows:— Should a hold-up bandit approach the cage behind which the teller is standing, the tongue 36 which actuates the trigger 32 may be depressed by the foot of the teller, thereby disengaging the hook 31 from the bracket 30 whereupon the tension of the coil spring 41 will immediately shoot the shield 20 in an upward direction to the position shown in dotted lines in Figure 3 and this movement will swing the trigger 45 in view of the fact that the pin 49 will trip the arm 48 of the trigger and move the overhanging tongue 47 out of engagement with the disc 43, whereupon the spring 42 will force the plunger 40 upwardly for firing the cartridge 9 within the cylinder 8 and eject the tear gas or other medium cut through the passage 7 and the discharge ports or apertures 5.

Should it be desired, a suitable signal, indicated in general by the letter S may be used in conjunction with the apparatus to be actuated when the shield 20 is sprung for elevation. This signal may be of any type desired, and is only shown in diagrammatic view in Figure 3 and may be placed at any suitable or convenient point without departing from the spirit of the invention.

It should be understood that certain detail changes in mechanical construction may be employed without departing from the spirit of the invention so long as these changes fall within the scope of the appended claim, and that other mechanical, electric, pneumatic, or other means may be employed for raising the shield to a protecting position in substitution for the spring 41, without departing from the spirit of the invention.

Having described the invention, what is claimed as new is:—

A device of the class described comprising a vertically movable shield, a pivotally mounted trigger engaging said shield for holding the same in an inoperative position, a treadle for actuating said trigger, a counter for supporting said shield, an expansible spring anchored at its respective ends to said counter, a shoe carried by the lower end of said shield, said spring extending under said shoe and adapted to automatically raise said shield to a protecting position as said trigger is released from said shield, a hanger track carried by said counter and extending parallel with said shield, and means carried by said shield and passing around said hanger track for guiding said shield in its sliding movement.
